Primary Examiner — Kendra Leslie Hamilton

(57) **CLAIM**

The ornamental design for a baby feeder, as shown and described.

DESCRIPTION

FIG. 1 is a top, front, left perspective view of a baby feeder showing my new design;

FIG. 2 is a bottom, rear, right perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is an enlarged top plan view thereof;

FIG. 8 is an enlarged bottom plan view thereof;

FIG. 9 is an enlarged view of detail “9” (identified in FIG. 1), shown at a greater scale for clarity of disclosure;

FIG. 10 is an enlarged view of detail “10” (identified in FIG. 1), shown at a greater scale for clarity of disclosure;

FIG. 11 is an enlarged view of detail “11” (identified in FIG. 2), shown at a greater scale for clarity of disclosure;

FIG. 12 is a top, front, left perspective view of the baby feeder of FIG. 1, shown exploded for clarity of disclosure;

FIG. 13 is a bottom, rear, right perspective view of the baby feeder of FIG. 2, shown exploded for clarity of disclosure;

FIG. 14 is a top, front, left perspective view of the baby feeder, shown in a first alternative condition of use; and,

FIG. 15 is a top, front, left perspective view of the baby feeder, shown in a second alternative condition of use.

The broken lines in the drawings depict elements of the baby feeder that form no part of the claimed design.

1 Claim, 15 Drawing Sheets
